UNITED STATES PATENT OFFICE.

HIRAM MYERS, OF SPRINGFIELD, OHIO.

CULTIVATOR.

SPECIFICATION forming part of Letters Patent No. 426,136, dated April 22, 1890.

Application filed October 7, 1889. Serial No. 326,270. (No model.)

To all whom it may concern:

Be it known that I, HIRAM MYERS, a citizen of the United States, residing at Springfield, in the county of Clark and State of Ohio, have 5 invented certain new and useful Improvements in Cultivators, of which the following is a specification.

My invention relates to improvements in cultivators.

10 The object of my invention is to provide a cultivator of simple construction which shall be capable of ready adjustment to any work required thereof and at the same time be capable of easy and rapid manipulation when 15 in operation.

My invention consists in the various constructions and combinations of parts herein-after described, and set forth in the claims.

In the accompanying drawings, which form 20 a part of this specification, Figure 1 is a side elevation of a cultivator embodying my invention, one of the carrying-wheels being removed. Fig. 2 is a plan view of the same. Fig. 3 is a partial sectional view of one of the 25 beams and its attachment shown in detail. Fig. 4 is a similar view showing the beam in a different position of adjustment, some of the parts being slightly modified in their construction. Fig. 5 is a transverse sectional 30 view on the line X X in Fig. 3. Fig. 6 is a detail view, partly in section, showing the manner of attaching the hangers to the main frame.

Like parts are represented by similar letters 35 of reference throughout the several views.

In the said drawings, A A represent the main frame of the device, which is essentially rectangular and preferably formed of gas-pipe joined together by elbow-connections, as 40 shown.

The operating parts of the cultivator are attached to the frame by means of hangers B B, each of which consists, essentially, of two U-shaped pieces a of flat metal, each provided 45 at their upper extremities with an eye or opening a', adapted to fit over the sides of the frame A A and be secured thereon in any desired position by a clamping-bolt a² or in any other well-known and suitable manner.

50 Secured in each of the hangers B, and extending across the U-shaped piece a in the lower rear corner thereof, are the wheel-sup-

porting spindles b. These spindles project out a suitable distance from the hangers B and support the carrying-wheels b'. Immediately forward of these spindles b in the opposite corner of each of the hangers is secured a bearing support c, journaled in suitable bearings c' in said hangers. These bearing-supports c are each provided with a semi-circular top or table c², having a circular depression c³ therein, in which rests a projecting boss d on the beam-supporting pieces D. The beam-supporting pieces D are each pivoted to the bearing-supports c by a bolt c⁵ 65 and are adapted to turn thereon, the said bolt passing through the center of the boss d and depression c³, as shown in Fig. 3.

C C are the beams, which are each pivoted at their inner ends to the beam-supporting 70 pieces D, the said beam-supporting pieces D being bifurcated and provided on each side with projecting flanges d', between which the beam C rests and to which it is connected by a pivot-bolt d².

Immediately back of the flanges d' and at right angles thereto are projecting lugs d³ on the beam-supporting pieces D. These projecting lugs d³ are each bored out to receive a spring-bolt d⁵, which passes through said 80 lugs and is provided with a spring d⁷, adapted to be compressed between the head of the spring-bolt d⁵ and one of the projecting lugs d³.

Connected to the end of each of the beams 85 C is a connecting-clip e, and extending from this clip to a similar clip e' on the spring-bolt d⁵ is a connecting-link e². The pivoted connection d² of the beam C is placed in line with the center of the spring-bolt d⁵, so that when the beam is parallel to said spring-bolt 90 d⁵ the connecting-link e² is also parallel thereto and the pivoted connections are in line. As the rear end of the beam carrying the cultivator-shovels is elevated the parts are brought to the position shown in Fig. 4, and 95 the spring-bolt d⁵ is, by the spring d⁷, forced outwardly and is connected with the link e, and the pivoted joint d² exerts a pressure on the beam C, which tends to raise the same and hold it in an elevated position. When 100 the beam C is lowered below the center, a reverse action is obtained, the spring being adapted to operate to force the beam downwardly and hold it in a downward position.

By the arrangement of the parts as thus described it will be seen that the spring acts with increased force as the beam is moved farther from the center in either direction.

5 The beam C rests above the spindle *b*.

Attached to the beam C and projecting downwardly under the spindle *b*, I provide a hook or **U**-shaped bearing *f* to prevent the beam and its supporting-pieces from turning 10 in a vertical plane in the bearing *c'*. Sufficient latitude, however, is left in said bearing *f* to permit the beam to be adjusted laterally about the pivoted connection *c*, as is desired.

15 Between the spindle *b* and the beam C, I preferably provide a friction-roller *f'*, journaled at each end on bearings *f*, and adapted to travel on the spindle *b* and roll thereon as the beam is moved laterally.

20 The tongue E is secured to the main frame A A, and is preferably attached thereto at the rear end so as to turn thereon, the front side of the frame being provided with upwardly-projecting flanges *h*, secured by set-

25 screws or otherwise to the frame A, and provided with a series of openings *h'*, by which the angular position of the tongue and frame may be adjusted, as desired.

The beams C are each provided with a suitable handle *k* and shovels *ll* of any well-known construction.

The hitch-rod *m*, extending from the frame A A to each of the hangers B, is provided for making the hitch, the said hitch-rod being 35 preferably connected at the bottom through a spring-connection *m'* in a well-known manner.

Having thus described my invention, I claim—

1. In a cultivator, the combination, with a 40 rectangular frame, of the **U**-shaped hangers depending below said frame and adjustably connected thereto at their upper extremities, wheel-supporting spindles in said hangers, and vertically and longitudinally adjustable 45 beams pivoted in said hangers, substantially as specified.

2. The combination, with a rectangular horizontal frame, of supporting-hangers each formed of two **U**-shaped depending pieces adjustably connected at their upper ends to said frame, each of said hangers being provided with a wheel-supporting spindle and a pivoted bearing-support, a beam-supporting piece pivoted to said bearing-support, and a 55 beam pivoted in said beam-supporting piece

at right angles to the pivoted connection between the beam-supporting piece and bearing-support, substantially as specified.

3. The combination, with the hangers, of a pivoted bearing-support having a laterally-adjustable beam-supporting piece pivoted thereto, a pivoted beam connected to said supporting-piece, a longitudinally-moving spring-bolt in suitable bearings directly in front of said beam, and a connecting-link from said spring-bolt to said beam, substantially as specified. 60

4. The combination, with the bearing-support journaled in the hanger, as described, of the beam-supporting piece pivoted thereto, the beam pivoted to said beam-supporting piece, and a longitudinally-moving spring-bolt supported in suitable bearings on said supporting-piece in line with the pivoted connection between the supporting-piece and beam, a spring on said bolt, and a connecting-link between said bolt and spring, substantially as specified. 70

5. The combination, with the hanger and a wheel-supporting spindle, of the bearing-support pivoted thereon, the beam-supporting piece laterally adjustable on said bearing-support, a spring-bolt in suitable bearings on said supporting-piece, a beam pivoted between projecting flanges on said supporting-piece, a connecting-link between said spring-bolt and the end of said beam, a friction-roller between said beam and spindle, and a bearing undersaid spindle connected to said beam, substantially as specified. 80

6. The combination, with a pivoted beam, of a longitudinally-moving spring-bolt held against lateral movement in suitable bearings, a spring connected to said spring-bolt, so as to be compressed by a longitudinal 95 movement thereof, and a connecting-link between said spring-bolt and the end of said beam, the beam end of said connecting-link being adapted to pass the center of said spring-bolt and bring the pressure of said spring on opposite sides of said beam as the beam is raised or lowered, substantially as specified. 100

In testimony whereof I have hereunto set my hand this 30th day of September, A. D. 1889. 105

HIRAM MYERS.
